UNITED STATES PATENT OFFICE.

HERMANN GUTSCHE, OF NEW ULYSSES, KANSAS.

WIRE-STRETCHER.

1,371,163.

Specification of Letters Patent.

Patented Mar. 8, 1921.

Application filed May 18, 1920. Serial No. 382,385.

To all whom it may concern:

Be it known that I, HERMANN GUTSCHE, a citizen of Germany, residing at New Ulysses, in the county of Grant and State of Kansas, 5 have invented new and useful Improvements in Wire-Stretchers, of which the following is a specification.

This invention relates to wire stretchers and the principal object of the invention is 10 to provide a device for stretching long strands of wire, either barbed or plain.

Another object of the invention is to provide means whereby the device can be used for splicing two strands of wire together 15 and for stretching a strand to a post.

This invention also consists in certain other features of construction and in the combination and arrangement of the several parts, to be hereinafter fully described, illustrated in the accompanying drawings and 20 specifically pointed out in the appended claim.

In describing my invention in detail, reference will be had to the accompanying 25 drawings wherein like characters denote like or corresponding parts throughout the several views, and in which:—

Figure 1 is a view showing the invention being used to stretch a wire to a post.

30 Fig. 2 is a view showing the device being used for splicing two strands of wire together.

Fig. 3 is a detail view of the hand lever and its attached parts.

35 Fig. 4 is a detail view of the post engaging member.

In the drawings 1 indicates a hand lever which is provided with a hole 2 adjacent its 40 end for receiving the short hook member 3 and with a hole 4 for receiving the long hook member 5. As shown the hooked end of the long member is arranged to extend in the longitudinal plane of the lever while the hook on the short member extends at right 45 angles to said plane. The lever is also provided with a hole 6 midway the distance between the two holes 2 and 4 to receive a link 7 which engages the wire holder 8. This holder is formed of a plate having one end 50 forked and bent over, as at 9, the ends of the fork being connected with the plate by the rods 10. The pin 11 is connected to one of these rods by the chain 12, said pin being adapted to hold the wire in the hole.

55 The post engaging member consists of a yoke 13 which is secured to a holder 14 which is formed similar to the holder before

described. An eye 15 is formed at one end of the yoke and a hook 16 is formed at the other end. The eye receives the end link of 60 a chain 17 and one of the other links is adapted to engage the hook 16 to connect the device with the fence post. A link 18 engages the end of the holder 14 and the other end of this link is connected to a chain 19. 65

When the device is to be used for stretching the wire so that it may be attached to a post, as shown in Fig. 1, the yoke 13 is connected with the post by means of its chain 17 and the wire is placed between the forks of 70 the holder 8 and held therein by the pin 11. The hooks 3 and 5 are then placed in engagement with a pair of the links of the chain 19 and the hand lever rocked back and forth to stretch the wire, the hooks 3 and 5 75 being placed in new links at the ends of the movements of the lever so that this movement will cause the lever and its attached part with the wire to travel toward the post.

Thus the wire will be stretched and may be 80 held in stretched condition while being nailed to the post. When the device is used for splicing the wire, as shown in Fig. 2, the holder on the handle is connected with one part of the wire while the holder on the yoke 85 is connected with the other part and then the handle is manipulated to bring the two portions together as will be understood.

The device may be used for stretching 90 barbed wire or plain wire and it will stretch long strands of wire so that it is not necessary to stretch from post to post.

It is thought from the foregoing description that the advantages and novel features of my invention will be readily apparent. 95

I desire it to be understood that I may make changes in the construction and in the combination and arrangement of the several parts, provided that such changes fall within the scope of the appended claim. 100

What I claim is:—

A wire stretcher of the class described comprising a hand lever, a pair of hooked members carried thereby, a wire clamp comprising a plate having a forked end with 105 the said end bent over to form a hook, a pin for holding the wire in the hook, a link connecting the clamp to the lever, a yoke member, a chain for connecting the same with a post and a length of chain connected with 110 said yoke member and adapted to be engaged by the hooked member.

In testimony whereof I affix my signature.
HERMANN GUTSCHE.
